UNITED STATES PATENT OFFICE.

ARTHUR PEART HOLDEN, OF TORONTO, ONTARIO, CANADA, ASSIGNEE TO THE HOLDEN-MORGAN COMPANY, LIMITED, OF TORONTO, ONTARIO, CANADA, A CORPORATION OF ONTARIO.

WRAPPER AND FOLDER.

1,085,261.

Specification of Letters Patent.

Patented Jan. 27, 1914.

Application filed August 11, 1913. Serial No. 784,019.

To all whom it may concern:

Be it known that I, ARTHUR PEART HOLDEN, of the city of Toronto, in the county of York and Province of Ontario, 5 Dominion of Canada, have invented certain new and useful Improvements in Wrappers and Folders; and I hereby declare that the following is a full, clear, and exact description of the same.

- 10 My invention relates to the formation of the end folds of a wrapper which has been previously formed to a tubular shape, *i. e.*, conformed to four sides of the article by any suitable mechanical or manual means; and 15 the object of the invention is to so form the end folds that the ends of one wrapper side will completely cover the folds formed by the ends of the other three sides for the effective sealing of the package ends.
- 20 In concurrent applications Serial Nos. 765,616, 776,970 and 780,572 various types of end folders have been shown and described; these end folders operating on the principle of exteriorly engaging the ends of one side 25 of a tubular wrapper and folding it against the ends of the article, then entering interiorly of the wrapper to define the lines along which the remaining folds are to be made and then interiorly engaging the 30 wrapper and tensioning it for the formation of the remaining folds.

In my present application, I employ end folders, operating on substantially the same principle as those described in the above applications, which after exteriorly engaging the ends of the bottom wrapper side and folding them against the ends of the article, enter interiorly of the remaining sides and define the lines along which the remaining 35 folds are to be made, and interiorly engage the ends of the top wrapper side, other folding means then exteriorly engaging the ends of the vertical wrapper sides and folding them inward beneath the top wrapper side 40 so that when the top wrapper side is closed against the package ends, it will completely cover the folds formed by the bottom and vertical wrapper sides.

Figure 1, is a perspective view of a tubular wrapper with the ends ready for folding; Fig. 2, is a perspective view of the wrapper shown in Fig. 1, with the ends of the bottom side folded against the ends of the article; Fig. 3, is a perspective view of

the same wrapper showing the ends of the 55 vertical sides folded inward beneath the ends of the top side; Fig. 4, is a perspective view showing the ends of the top side closed against the package ends; Fig. 5, is a side elevation of the folder with the parts in 60 their normal position; Fig. 6, is an end elevation of the folder with the parts in their operative position.

Like characters of reference refer to like parts throughout the specification and drawings.

The tubular wrapper shown in Fig. 1 consists of a bottom side *a*, a top side *b* and two vertical sides *c*. This tubular wrapper is preferably conformed to four 70 sides of the article by any suitable mechanical or manual means, satisfactory mechanical means for this purpose being shown and described in applications for Letters Patent of the United States, Serial Nos. 776,970 75 and 780,572.

When the wrapper has been conformed to a tubular shape, around the article, as shown in Fig. 1, end folders similar to those shown in Figs. 5 and 6, exteriorly engage the ends 80 *a'* of the bottom side *a* and fold them against the ends of the article contained within the wrapper, and at the same time tuck in the lower halves of the ends *c'* of the vertical sides *c* and form the tubular wrapper to the shape shown in Fig. 2. The end folders then enter interiorly of the wrapper to define the vertical lines 1 along which the ends *c'* of the vertical sides *c* are to be 85 in-folded and to define the horizontal lines 2 along which the ends *b'* of the top side *b* are to be down-folded.

The folder shown in Figs. 5 and 6 consists of a fold-forming element *d* provided with a bracket *d'* vertically slidable on guide 95 rods *d''* and actuated by an operable lever *d³*. The folder *d* moves under the influence of the lever *d³* into engagement with the end *a'* of the bottom side *a* and by exteriorly engaging the end of the bottom side folds 100 it against the end of the article. Forming part of the folder *d* are two arms *o* having at their upper ends bosses *p* for the hinge pins *q* which oscillatingly connect the arms *r* to the arms *o*. Forming part of the arms *r* 105 is a moving folding member *d⁴* which when the folder parts are in their contracted position lies in a parallel plane with the fold-

forming element d and which when the folder parts are expanded occupies a position at substantially right angles to the fold-forming element d as shown in Fig. 6. One of the hinge pins q is provided with a pinion t engaged by a suitably operated rack u which when moved in one direction closes the folder part d^4 against the fold-forming element d and when moved in the other direction brings the folder part d^4 into a position at right angles to said fold-forming element.

Pivoted to the arms o are folders v provided with cranks w having toothed segments w' actuated by suitable operating mechanism x . When the folders are raised by the operating lever d^3 , the fold-forming elements d exteriorly engage and fold the ends a' of the side a . The fold-forming elements d together with the folder parts d^4 then enter interiorly of the wrapper to define the lines along which the vertical sides are to be folded. The rack u is then actuated to rotate the pinion t and move the folder parts d^4 into a position at substantially right angles to the fold-forming elements d whereby the folder parts d^4 will interiorly engage and tension the top wrapper side and define the lines along which it is to be down-folded and the vertical sides c in-folded. The actuating mechanism x is then operated to move the folders v inwardly across the fold-forming element d , the inward movement of the folders v exteriorly engaging the ends c' of the vertical sides c and infolding them as shown in Fig. 3. During the infolding of the ends c' of the vertical sides c the movement of the rack u is reversed which has the effect of lowering the folder part d^4 into a plane parallel with the fold-forming element d and close the end b' against the package ends. The folding inward of the ends c' of the vertical sides c permits the ends b' of the top side b to retain their original shape which as shown in Figs. 1, 2 and 3, correspond in dimensions with the package ends. Suitable means such as the pressers shown in the above applications #776,974 and #780,572 are then employed to press the ends b' against the folded ends of the remaining sides until sealed thereto. A fold of this character is advantageous for many purposes, and particularly so when the package ends are to be sealed, as it is possible to gum the ends b' of the top side b and press them against the package ends until they adhere thereto, there being in a case of that kind, only a comparatively small quantity of gum used. It is also possible to secure the package ends by means of labels adhering to the outer surfaces of the ends b' of the top side b and to the outer surface of the bottom side a or vertical sides c , and when waxed paper is used, it is possible to

heat the waxed ends b' of the top side b and press them against the folds formed by the other sides until they adhere together and it is also possible by the employment of a relatively small squirt of wax to insure the adhesion of the ends b' to the package ends.

When the rack u has lowered the folder part d^4 into a plane parallel with the fold-forming element d , the end b' of the top wrapper side lies flat against the package end and the operating lever d^3 is then actuated to lower the end folder out of engagement with the wrapper. This is effected by the peculiar hinge construction of the fold-forming element d and folder part d^4 which avoids any direct connection between the folder part and fold-forming element, so that when they are in parallel planes there will be a gap at their inner ends to permit of each part being separately withdrawn from the folded wrapper end. During the formation of the folds, the fold-forming element d occupies a position between the outer side of the folded wrapper end a' and the inner side of the infolded wrapper ends c' , and the folder part d^4 occupies a position between the wrapper end b' and the infolded wrapper ends c' . To maintain the folded formation of the wrapper ends during the return of the folder to its starting position the arms o and r are spaced from the fold-forming element d and folder part d^4 so that they will during the formation of the end folds occupy a position entirely clear of the wrapper to obviate any possibility of coming into contact therewith when the fold-forming element d and folder part d^4 are being withdrawn from the folds.

Having thus fully described the nature of my invention, what I claim as new and desire to secure by Letters Patent, is:—

1. A folder, for closing the ends of a tubular wrapper, comprising a fold-forming element and actuating means therefor, whereby it will exteriorly engage and fold the end of one side of the tubular wrapper and then enter interiorly of the remaining sides to define the lines along which they are to be folded, an oscillating part in a plane parallel with the said fold-forming element when the folder enters interiorly of the wrapper, and means actuating the oscillating part whereby it will assume a position in angular relation to the fold-forming element and interiorly engage one side of the wrapper and tension it.

2. A folder, for closing the ends of a tubular wrapper, comprising a fold-forming element and actuating means therefor, whereby it will exteriorly engage and fold the end of one side of the tubular wrapper and then enter interiorly of the remaining sides to define the lines along which they are to be folded, an oscillating part in a plane

parallel with the said fold-forming element when the folder enters interiorly of the wrapper, means actuating the oscillating part whereby it will assume a position in 5 angular relation to the fold-forming element and interiorly engage one side of the wrapper and tension it, and means coöperating with said folder to exteriorly engage two op-

posed wrapper sides and fold them inward beneath the side tensioned by said oscillating part. 10

Toronto, July 29th, 1918.

ARTHUR PEART HOLDEN.
